COOLING UNIT

Rollin H. Norris, Schenectady, N. Y., assignor to
General Electric Company, a corporation of
New York

Application February 27, 1940, Serial No. 321,029

1 Claim. (CL 62—126)

My invention relates to cooling unit, and particularly to refrigerant distributing arrangements for cooling units having a plurality of evaporating elements or conduits.

Cooling units such as those employed in air conditioning systems commonly comprise a plurality of straight tubes provided with fins for extending the effective heat transfer surface thereof and connected by suitable return bends to provide one or more continuous paths for the refrigerating fluid. When a cooling unit of this type is connected in the circuit of a refrigerating machine as an evaporator, it frequently is desirable to supply refrigerant to the entire unit under control of a single expansion valve. The several conduits may be connected to provide a single long conduit. However, this arrangement is objectionable since it results in a high pressure drop from the inlet to the outlet of the conduit and, therefore, inefficient use of the major portion of the conduit. One arrangement for avoiding long refrigerant conduits in a cooling unit is to connect the several turns in such a manner as to provide a plurality of parallel paths. This arrangement, however, makes it necessary to provide an additional distributing device for insuring equal distribution of both liquid and gaseous refrigerant to all the parallel paths. Furthermore, the results obtained from the parallel arrangement of the conduits and the separate distributing device may not be entirely satisfactory because the low velocities prevailing near the inlet ends of the conduits result in relatively low coefficients of heat transfer between the refrigerant and the conduit near the inlet end and consequently in less effective use of the heat transfer surface.

It is an object of my invention to provide a cooling unit for refrigerating systems which comprises a plurality of evaporating tubes or conduits and an improved arrangement for facilitating the efficient use of the heat transfer surface of the entire unit.

Another object of my invention is to provide a cooling unit for refrigerating systems having a plurality of evaporator tubes or conduits and an improved arrangement for securing efficient use of the entire heat transfer surface of the unit without the necessity of providing a distributing header or other device between the expansion valve and the conduits.

Further objects and advantages of my invention will become apparent as the following description proceeds, and the features of novelty which characterize my invention will be pointed

out with particularity in the claim annexed to and forming a part of this specification.

For a better understanding of my invention, reference may be had to the accompanying drawing in which Fig. 1 shows diagrammatically and partly in section an air conditioning system provided with a cooling unit embodying my invention; Fig. 2 is a bottom plan view on the line 2—2 of Fig. 1; and Fig. 3 is an enlarged sectional view of one of the T-connections employed in the cooling unit.

In general, the cooling unit as illustrated comprises a plurality of conduits or tubes connected so that liquid refrigerant is admitted under control of a single thermostatic expansion valve and, after passing through one tube, is divided equally and distributed to two other tubes and after passing through each of these two tubes is again divided and distributed to additional tubes, the vaporized refrigerant being withdrawn through a suction manifold to which the final group of tubes is connected. This arrangement insures even distribution of refrigerant at each dividing point of the refrigerant stream and, furthermore, provides an increased cross-sectional area for facilitating the flow of gaseous refrigerant as it is vaporized. Higher velocities of refrigerant flow in the tubes near the inlet end of the cooling unit are obtained by this arrangement than would be obtained with all the tubes in parallel and this arrangement, therefore, uses more effectively the heat transfer surface of the unit.

Referring now to the drawing, in Fig. 1 I have shown an air conditioning system including a duct 10 provided with a fresh air inlet 11 and a room or return air inlet 12 for withdrawing air from the room to be conditioned. A cooling unit 13 is arranged within the duct 10 to cool the air passing therethrough and a fan 14 driven by a motor 15 is provided for circulating the air and returning it to the room through a discharge duct 16. The cooling unit 13 is connected in the refrigerant circuit of a refrigerating machine 17 including a compressor 18 driven by a motor 19 and arranged to discharge compressed refrigerant into a condenser 19 surrounded by a water cooling jacket 20 through which cooling water flows as indicated by the arrows. The refrigerant is cooled and liquefied in the condenser 19 by the circulation of water through the jacket 20 and is discharged into a liquid receiver 21 from which it flows through a liquid line 22 to the cooling unit 13 under control of a thermostatic expansion valve 23. The valve 23 operates

to maintain a predetermined number of degrees of superheat of the vaporized refrigerant withdrawn from the cooling unit 15 through a suction line 24 and returned to the compressor, the valve being provided with a thermal element or feeler bulb 25 secured in heat exchange relation to the suction line adjacent the outlet of the evaporator.

The cooling unit 13 comprises a plurality of tubes or conduits numbered consecutively from 26 to 32 inclusively. Each of these tubes has been shown as comprising four straight runs or passes connected by suitable end turns to provide a flat sinuous coil. The planes of the several flat coils are arranged parallel to the direction of flow of the air through the duct 10. The straight portions of the conduits pass through and are secured in heat exchange relation with a plurality of fins 33 which provide increased effective heat transfer surface for the evaporator. The conduits 26 to 32, inclusive, are connected in such a manner that the middle conduit 29 receives the entire flow of liquid and gaseous refrigerant entering the evaporator from the expansion valve 23. After passing through the conduit 29, the refrigerant stream is divided equally at a T-connection 34 and flows into the conduits 27 and 31. After passing through the conduits 27 and 31, the refrigerant streams are again divided equally by T-connections 35 and 36 respectively, refrigerant then flowing through conduits 26, 28, 30 and 32 to the suction manifold 24. It is to be noted that the two conduits receiving refrigerant from any one conduit are arranged symmetrically with respect to the one conduit. The T-connections 34, 35 and 36 are of identical construction, the T-connection 34 being shown in detail in Fig. 3. In order to facilitate the equal distribution of both liquid and gaseous refrigerant flowing from the conduit 29 to the conduits 27 and 31, a vertical ridge or dividing element 37 is formed in the T-connection on the central axis of and in a direct line with the conduit 29. In order to neutralize any effect of gravity to produce uneven distribution of refrigerant, I prefer to arrange the T-connections in a horizontal plane so that the entering and both the leaving streams of the refrigerant flow horizontally. Furthermore, it is to be noted that each of the T-connections 34, 35 and 36 receives refrigerant in a straight line from a straight portion of the conduits 29, 27 and 31 respectively. The refrigerant flowing from the expansion valve and throughout the evaporating conduits comprises a mixture of liquid and gaseous components, the gaseous component increasing in volume throughout the length of the evaporator from the inlet to the outlet due to the vaporization of the liquid upon absorption of heat from the air flowing through the duct 10. Since the refrigerant entering any one of the T-connections must first pass through a considerable length of straight conduit which passes through the air stream, the velocity effects due to the passage of the refrigerant around a return bend are minimized at the T-connections and both the liquid and gaseous components of the mixture tend to be distributed evenly at the T-connections. It will be noted that the cross-sectional area of the refrigerant path is doubled at each of the T-connections. It will be evident that with the greater cross-sectional area, there is less pressure drop along the refrigerant path from the inlet to the outlet and consequently, it is possible for a given total pressure drop from

the inlet to the outlet of the evaporator to obtain greater velocities of flow in the first portion of the evaporating path as represented by the conduit 29. The heat transfer coefficient along the portion of the evaporating path formed by the conduit 29 is therefore substantially greater than would be possible for a single tube if all the tubes were connected in parallel.

During the operation of the air conditioning systems shown in Fig. 1, air is circulated through the duct 10 by operation of the fan 14 and refrigerant is circulated through the cooling unit 13 by operation of the compressor 11. The thermostatic expansion valve 23 maintains the rate of flow of refrigerant to the cooling unit such that the vaporized refrigerant in the suction manifold 24 will have a predetermined number of degrees of superheat. The mixture of liquid and gaseous refrigerant entering the conduit 29 from the valve 23 absorbs heat from the air passing through the duct, thereby increasing the gaseous component in the refrigerant mixture at the discharge end of the conduit 29 where the mixture is divided equally. The refrigerant then flows to the conduits 27 and 31 where further heat is absorbed and more of the liquid vaporized, the streams being again divided equally at the T-connections 35 and 36 so that the streams of liquid and gaseous refrigerant flowing into the conduits 26, 28, 30 and 32 contain equal liquid and gaseous components. The vaporized refrigerant is finally discharged from the outlets of the conduits 26, 28, 30 and 32 and enters the suction line 24. By arranging the connections 35 of the refrigerant conduits in the manner described, the heat transfer coefficients and refrigerant velocities throughout the cooling unit are more nearly equal, and efficient use is made of the entire evaporator surface. The variation in refrigerant velocities and in the coefficients of heat transfer along each of the conduits 26 to 32, inclusive, is minimized and as a result each of the conduits tends to carry its proportionate share of the load of the cooling unit.

It is apparent from the foregoing that I have provided a simple and effective arrangement for facilitating the even distribution of refrigerant among a plurality of conduits or tubes and for making effective use of the entire heat transfer surface of an evaporator without the necessity of providing any distributing apparatus external to the evaporator coils.

While I have shown my invention in connection with an air conditioning system, other applications will readily be apparent to those skilled in the art. I do not, therefore, desire my invention to be limited to the particular construction shown and described and I intend in the appended claim to cover all modifications within the spirit and scope of my invention.

What I claim as new and desire to secure by Letters Patent of the United States, is:

A cooling unit for a refrigerating system comprising an odd number of similar conduits distributed evenly over the path of a medium to be cooled and having straight portions arranged across the path of the medium, an inlet for admitting liquid refrigerant to the middle one of said conduits, a distributor at the outlet end of said middle conduit for supplying substantially equal quantities of the refrigerant discharged therefrom to two others of said conduits located symmetrically on either side of said middle conduit, and a distributor at the outlet of each of said two conduits for again dividing the refrigerant.

erant equally to two further ones of said conduits arranged symmetrically with respect to the corresponding one of said two conduits whereby each stream of refrigerant before it is divided must pass through a conduit in heat exchange with the medium to be cooled and the divided streams of refrigerant are distributed symmet-

rically across the path of the medium to be cooled, and means for collecting vaporized refrigerant discharged from said further ones of said conduits and for removing the refrigerant from said unit.
